UNITED STATES PATENT OFFICE.

BERTHA R. DODGE, OF BROOKLYN, NEW YORK.

COMBINED STOCKING AND OVERSHOE.

Application filed March 26, 1925. Serial No. 18,609.

This invention relates to a combined stocking and overshoe. An object of the invention concerns the provision of simple and efficient footwear which combines the utility 5 of an overshoe and a stocking in one article.

The invention concerns the provision of simple and efficient means whereby a stocking and an overshoe are combined in one article which is neat and attractive in appearance and economical to manufacture.

Another object concerns the provision of a simple and efficient article which can be worn in wet weather to protect not only the feet but the legs of the wearer and have 15 the appearance of a heavy cloth stocking combined with rubbers.

The invention is illustrated in the drawings, of which—

Figure 1 is a perspective view of the article on the limbs of a wearer;

Fig. 2 is a partial elevation of the upper end of the stocking;

Fig. 3 is a section of the foot of the article; and

Fig. 4 is a transverse section on the line 4—4 of Fig. 3.

The form of the invention shown in the drawings is a preferred form, although it is understood that modifications in the construction and arrangement of the parts and in the character of the materials used may be adopted without departing from the spirit of the invention as set forth in the appended claims.

In the preferred form of the invention shown in the drawings, I utilize a stocking 10, preferably of the kind known as cloth stockings, having an upper leg-encircling band 12 adjustably clamped on the leg by means of an elastic 13 and at the same time 40 readily opened at the top by means of buttons 14 and loops 15.

The lower end of this stocking is, by any suitable method and apparatus, substantially integrally connected to a rubber or overshoe 16. This overshoe may be of any desired type, the form shown being preferably adapted for women's use. In the form shown, the lower end of the stocking is properly cemented to the inner surface of 45 the sides of the overshoe, and then a rubber lining 17 is disposed against the stocking as shown. The particular manner in which these layers of rubber and the layer of 50 stocking are connected together is immaterial, although the form shown is desirable. In this way a person can slip on the article and protect not only the feet but also the limbs from the weather and at the same time maintain the appearance of wearing 55 this particular type of stocking. The fact that the stocking at its lower end is provided with a waterproof layer of rubber makes the article more effective to prevent 60 getting the feet wet than if the shoe itself 65 were exposed to the moisture. It furthermore combines the idea of a heavy stocking and a rubber in one article. This invention 70 provides a protection especially adapted for cold weather to wear over a shoe and stocking and can be regulated to any desired size from the ankle to the knee.

What I claim is:—

1. An article of footwear, which comprises an overshoe, a stocking cemented at 75 its lower end to the overshoe, and an inner lining of rubber at the lower end of the stocking.

2. An article of footwear which comprises an overshoe, a stocking disposed at its lower 80 end within the overshoe and cemented thereto, and a waterproof lining within the lower end of the stocking.

BERTHA R. DODGE.
